BENDING MACHINE

George E. Goin, Detroit, Mich., assignor to Peninsular Metal Products Corporation, a corporation of Michigan

Application March 27, 1935, Serial No. 13,214

24 Claims. (Cl. 153—32)

This invention relates to bending machines and particularly to machines for bending substantially straight metal strips, of tubular or any other cross section, to a desired annular or other form.

5 The term "annular", as herein used, designates any member forming a closed or approximately closed loop, whether circular or of other form.

An object of the invention is to provide a fixed forming plate having an edge of the contour to be imparted to the work, and to provide for actuation around said edge, of a carriage which mounts mechanism for pressing the work against said edge.

Another object is to adapt the last mentioned 15 mechanism to yieldably hold the work against the forming plate, pneumatically or otherwise, under regulable pressure.

A further object is to adapt said carriage to be 20 motor driven and to permit, by a comparatively simple mechanism, the bending operation to be performed under a powerful leverage, minimizing the required motive power.

A further object is to provide an improved device for maintaining a fixed position of the end 25 portion of the work initially applied to the forming plate, said device providing for a quick clamping and unclamping of such end portion.

A further object is to provide an improved 30 bending mandrel for insertion in work of slotted tubular form and holding such work against the forming plate, and to mount such mandrel in a suitable holder on said carriage.

A further object is to assemble a propelling 35 mechanism for said carriage upon a second carriage, and to effect an articulated drive connection between the two carriages facilitating travel around curves of short radius.

These and various other objects the invention attains by the construction hereinafter described, 40 and illustrated in the accompanying drawings, wherein:

Fig. 1 is a top plan view of the machine, showing a length of molding partially bent to the form of a frame for a motor vehicle window.

45 Fig. 2 is a fragmentary vertical sectional view of the machine, particularly showing the carriage, its guide means and mechanism on the carriage for applying a bending stress to the work, the section being taken on the line 2—2 of Fig. 1.

50 Fig. 3 is a vertical sectional view, taken upon the line 3—3 of Fig. 1, and particularly showing the propelling unit for the carriage and its articulated connection to the carriage.

Fig. 4 is a cross sectional view of the machine, 55 taken on the line 4—4 of Fig. 1.

Fig. 5 is a horizontal section taken on the line 5—5 of Fig. 3, and primarily showing a carriage and driving means therefor.

Fig. 6 is a fragmentary vertical section taken on the line 6—6 of Fig. 1, and particularly showing a clamp for securing an end portion of a molding strip, preliminary to a bending operation.

Fig. 7 is a horizontal sectional view of the same, taken on the line 7—7 of Fig. 6.

Fig. 8 is a cross section taken upon the line 8—8 of Fig. 2 and particularly showing a mandrel inserted in the work, and a holder for such mandrel.

In these views, the reference character 1 designates a base plate, which is centrally formed with a heavy upstanding flat-topped rib 2. Rigidly secured on such rib by bolts 3 or the like is a bending form consisting of a heavy metal plate 4, of the size and shape to be imparted to the work. The cross-sectional form of the work may vary widely, according to its purpose, there being illustrated a length of tubular sheet metal molding 5, approximately triangular in cross section with edges spaced to provide a slot 6, coextensive in length with the molding. The plate 4 projects marginally to a uniform extent beyond the rib 2, and has its peripheral edge curved downwardly from the top face of the plate to conform with a correspondingly curved wall of the molding. (See Fig. 2.)

An end portion of the molding is initially insertable in a chamber 7, opening in a shoulder 7a which interrupts the edge face of the plate 4. From the outer wall of such chamber, there projects a rib 8, proportioned to pass through the slot 6, and carrying a core 9 proportioned to fit snugly within the molding. An eccentric 10 within the chamber 7 engages a clamping block 11, conforming to the curved pressure-receiving wall of the molding, and is adapted to clamp said wall tightly between said block and core. The eccentric is fast on a vertical shaft 12 projecting sufficiently above the plate 4 for engagement by an actuating tool 13.

To apply a bending stress to the work, there is slidably inserted therein a mandrel 14, snugly conforming to the shape of the molding. Said mandrel is sufficiently elongated to reinforce the molding and hold it to shape for some distance 50 in advance of the point of application of the bending stress. Integral and coextensive in length with the mandrel is a rib 15, which projects through the slot 6 and fits into a groove 16 of a holder 17, being pivoted on the latter and 55

afforded a limited swinging in the groove by a pin 18 vertically mounted in said holder. The mandrel is preferably articulated, having a relatively short trailing section 19 connected to the 5 main mandrel section by a link 20, allowing the trailing section to conform to such curvature as is imposed on the work by the main section. Swinging of the trailing section away from the 10 forming plate beyond alignment with the main section is prevented by a forward extension 21 on the rib of the trailing section, adapted to seat on the rib of the main section.

The mandrel holder is mounted in a carriage adapted to be driven around the work-engaging 15 edge of the forming plate, and having upper and lower projections 22 and 23 adapted to respectively overlap and underlap said plate. Between 20 said projections and facing the edge of the forming plate, is snugly inserted the mandrel holder, as best appears in Fig. 2. A lug 24 projecting from said holder, forwardly of the carriage mounts a screw 25 terminally bearing against the carriage to transmit its travel to the holder, and by adjusting said screw, the holder may be adjusted in the direction of carriage travel to accurately locate the mandrel relative to the point of application of bending stress.

To stress the molding against the forming plate, there is freely engaged with the outer face 30 of the mandrel holder, a pin 26, slideable in the carriage to and from the mandrel. Pivoted upon the outer face of the carriage, at 27a, is an approximately vertical lever 27 having a short work arm pivoted to said pin and a long power 35 arm pivoted to a short piston rod 28 carried by a piston 29, and axially projecting from a cylinder 30, in which this piston reciprocates. The cylinder surmounts the projection 22 and is adapted to receive compressed air (or some other 40 energizing fluid) through a flexible tube 31 connected to the inner head of the cylinder. Said tube extends to some elevated point of supply (not shown) and has sufficient play to accommodate itself to the circuit traversed by the carriage. A valve 32 in any suitable location permits 45 regulation of the applied fluid pressure. Thus it is seen that a powerful but fully regulable pressure is applied to hold the work against the forming plate and may be uniformly maintained throughout a bending operation, there being 50 ample resiliency in the means applying the pressure to compensate for slight inaccuracies in either the machine or the work.

To resist the outward stress reacting on the 55 carriage from the thrust applied to the pin 26, a pair of rollers 33, journaled on the carriage bear against the inner faces of a pair of tracks 34, rigidly secured by screws 35 to the top and bottom faces of the plate 4, adjacent to its edge. Said rollers are journaled on a pair of vertically 60 aligned pins 36, one of which is mounted fast in each of the projections 22 and 23. Tilting of the carriage is prevented by engagement of the tracks 34 between the projections 22 and 23, 65 and further by engagement of a heavy guide rail 37 between upper and lower arms 38 and 39 integrally and outwardly projecting from the carriage. Said rail is formed at suitable intervals with outwardly and downwardly projecting lugs 70 40 which are bolted at 40a to the base plate near its outer edge, and space the rail above the base plate.

For driving the carriage, a driven sprocket wheel 41 meshes with a chain 42 fixed upon the 75 inner face of the rail 37 and continuously ex-

tending around said face. Said sprocket wheel with its drive mechanism and a carriage for such mechanism forms a propelling unit for the first-mentioned carriage, as will presently appear. The sprocket wheel is fast on a vertical shaft 43 journaled in a pair of plates 44 and 44a respectively slidably engaging the top and bottom faces of the rail 37, a short distance rearwardly of the first-mentioned carriage, and said plates are integrally connected by front and rear posts 45 and 45a. Above and below the sprocket wheel and between said plates, a pair of rollers 46 are fast on the shaft 43, the upper of said rollers being fitted between the rail 37 and the lower track 34 and the lower roller fitting between the rail and 15 an annular track 47, which seats upon a shoulder 48 formed on the base plate adjacent to and surrounding the rib 2. Screws 49 or the like rigidly secure the track 47 on its seat. The plate 44 extends outwardly considerably beyond the plate 20 44a to mount an electric motor 50, which through grooved pulleys 51 and a V belt 52 drives a shaft 53, mounting a worm 54. The latter meshes with a worm-wheel 55 fast on the upper portion 25 of the shaft 43, said worm and worm wheel 55 being enclosed in a casing 56 surmounting a tubular post 57, integrally rising from the plate 44. A pair of vertically spaced arms 58 project respectively from the posts 57 and 45, and establish an articulated drive connection between the 30 two carriages, the upper of said arms terminally engaging in a slot 59 formed in the projection 22 of the leading carriage and the lower of said arms engaging a bracket 60 carried by and beneath the projection 23. A pair of vertically 35 aligned pins 61 pivotally connect the arms 58 to the leading carriage, completing an articulated drive between the two carriages allowing them to traverse a quite angular bend.

In operation of the described machine, a length 40 of molding is first slid over the sectional mandrel 14, 19, and an end portion of such length is inserted in the chamber 1, so as to receive the core 9. Air is now admitted to the cylinder 30, causing the pin 26 to apply a predetermined pressure 45 to the mandrel holder and leading mandrel section 14, to hold the inner wall of the molding against the bending form. The point of application of pressure to the leading mandrel section is sufficiently close to the rear end of said section to permit the desired bending of the molding rearwardly of said point. That portion of the leading section forward of the pressure point prevents the bending stresses from distorting the straight portion of the molding, and the trailing 50 section of the mandrel safeguards the bent portion 55 of the work from distortion.

Upon energization of the motor 50, the sprocket wheel 41 is driven, advancing along the chain 42 and carrying with it the rearward carriage. 60 This type of drive for said carriage affords the motor a powerful leverage, which is further augmented by the described worm and worm-wheel gearing. The forward carriage is pushed ahead of the rear one by the arms 58, and thus the 65 molding is progressively wrapped around the bending form. The articulated drive connection between the two carriages permits their travel, without binding, around curves of considerable angularity. As best appears in Fig. 2, the upper 70 track 34 sufficiently overhangs the work to prevent its upward distortion under bending stresses, and to safeguard the bent portion of the work from upwardly escaping from the bending form.

As appears in Fig. 1, the end portions of the 75

frame formed by the bent molding overlap to some extent. This is in compensation for the resiliency of the frame, which expands sufficiently on removal from the machine to bring the ends into substantial alignment.

5 The annuli formed by tracks 34 and 47 and by the guide rail 31 are coaxial and parallel with the work-engaging edge of the bending form.

In removing a completed frame from the machine, said frame is first raised clear of the plate 10 4, and its ends may then be readily sprung apart to clear the forward carriage.

As compared to apparatus for manually bending molding and the like, the described machine 15 greatly reduces labor, and considerably increases the output of bent frames.

As compared to present types of motor driven bending machines, the described machine greatly reduces complexity and cost.

20 The terms "rack" and "gear" are used in the following claims in a sufficiently broad sense to apply respectively to the chain and sprocket wheel which have been described and shown.

The invention is presented as including all 25 such modifications and changes as come within the scope of the following claims.

What I claim is:

1. A bending machine for elongated work comprising a bending form having an edge of the 30 contour to be imparted to the work, a carriage, means for guiding the carriage along said edge, means for driving the carriage along said edge, a pin 35 slideable in the carriage transversely to said edge for pressing the work against said edge, and means on the carriage for yieldably applying pressure to the pin.

2. A bending machine for elongated work comprising a bending form having an edge of the contour to be imparted to the work, a pair of 40 tracks on the bending form at opposite sides of and conforming to said edge, a carriage having projections forming an opening receiving the track-mounting portion of the bending form, a pair of axially aligned rollers mounted on said 45 projections and engaging the tracks to resist movement of the carriage from said edge, means on the carriage for pressing the work against said edge, and means for driving the carriage along said edge.

50 3. A bending machine comprising a bending form having a work-engaging periphery, two carriages adapted to travel along said periphery, guide rollers on the carriages, a track engaged by the guide rollers of both carriages, means on one of the carriages for driving it around said periphery, an articulated drive connection between the two carriages, and means on the other carriage for pressing the work against said periphery.

60 4. A bending machine comprising a bending form having a work-engaging periphery, means for holding work against said periphery, a carriage carrying such means, a second carriage adapted to follow the first mentioned carriage, means for guiding both carriages along said periphery, an articulated drive connection between the two carriages, and drive mechanism for the following carriage, mounted thereon.

70 5. A machine for bending a length of longitudinally slotted tubular molding comprising a bending form having a work-engaging periphery, a mandrel slideable in the molding to progressively press it against said periphery, a holder on which the mandrel is pivoted to conform itself to said periphery, a carriage, means for actuating the

carriage along said periphery, means on the carriage for applying pressure to the holder to press the mandrel against the molding, and a member for actuating the mandrel holder with the carriage, adjustable in the direction of travel of the carriage to vary the point of application of pressure to the mandrel.

5 6. A bending machine for elongated work comprising a bending form having an edge of the contour to be imparted to the work, a carriage, 10 means for guiding the carriage along said edge, means on the carriage for progressively conforming the work to said edge, a rack extending substantially parallel to said edge, a gear engaging the rack, a support rotatively mounting the gear, 15 means for rotating the gear to drive the support along the rack, and a driving connection from the support to the carriage, flexible to afford a relative angular movement of the carriage and support in their travel along said edge.

20 7. A bending machine for elongated work comprising a bending form having an edge of the contour to be imparted to the work, a carriage, means for guiding the carriage along said edge, means on the carriage for progressively conforming the work to said edge, a rack extending substantially parallel to said edge, a gear engaging the rack, a shaft carrying the gear, a pair of guide rollers on the shaft one at each side of the gear, a rail carrying the rack and engaged by the rollers, a support for the shaft, a driving connection from the support to the carriage, and means for rotating the shaft to advance the gear and its support along the rack.

25 8. A bending machine for elongated work comprising a bending form having an edge of the contour to be imparted to the work, a carriage, means for guiding the carriage along said edge, means on the carriage for progressively conforming the work to said edge, a rack extending substantially parallel to said edge, a gear engaging the rack, a support rotatively mounting the gear, 40 a driving connection from the support to the carriage, means for rotating the gear to advance its support along the rack, a rail carrying the rack, a track spaced from the rail toward the bending form, and a guide roller on the support, engaged between the rail and track.

30 9. A bending machine for elongated work comprising a bending form having an edge of the contour to be imparted to the work, a carriage, means for guiding the carriage along said edge, means on the carriage for progressively conforming the work to said edge, a chain fixed in a substantially parallel relation to said edge, a sprocket 55 wheel operatively engaging said chain, a support rotatively mounting the sprocket wheel, a driving connection from the support to the carriage, and means for rotating the sprocket wheel to advance its support along the chain.

60 10. A bending machine for elongated work comprising a bending form having an edge of the contour to be imparted to the work, a carriage, means for guiding the carriage along said edge, means on the carriage for progressively conforming the work to said edge responsive to advance of the carriage, a rack extending substantially parallel to said edge, a gear engaging the rack, a motor driving the gear to advance it along the rack, a support for the motor and gear, and a 70 connection from the support to the carriage for advancing the carriage with the gear.

65 11. A bending machine for elongated work, comprising a bending form having an edge of the contour to be imparted to the work and hav- 75

- ing opposite sides receding from such edge, a pair of tracks rigidly secured to the form at said opposite sides and conforming to the contour of said edge, a carriage movable along the edge, 5 guide members on the carriage engaging the tracks to maintain proximity of the carriage to said edge, means for driving the carriage along the edge, and means on the carriage for progressively conforming the work to said edge.
10. 12. In a bending machine for elongated work, a bending form having an edge of the contour to be imparted to the work, a rail spaced from such edge and conforming to its contour, a carriage movable along such edge, a track rigidly 15 carried by the bending form and extending along such edge, means for driving the carriage along such edge, means on the carriage for progressively conforming the work to such edge, guide means on the carriage engaging the track, and guide 20 means on the carriage engaging the rail.
13. A bending machine as set forth in claim 12, said track and rail coacting to maintain a fixed proximity of the carriage to said edge.
14. In a machine for bending work to an approximately annular form, a base plate, a support projecting from the central portion of such plate, a bending form rigidly mounted on the support in spaced relation to such plate and having an approximately annular periphery of 25 the contour to be imparted to the work, a rail rigidly carried by the base plate and forming an annulus, substantially conforming in contour and spaced outwardly from said periphery, a carriage engaged with the rail for travel along said periphery, means for driving the carriage, and means on the carriage for progressively conforming the work to said periphery.
15. A bending machine for elongated work comprising a bending form having an edge of the contour to be imparted to the work, a rack 30 extending parallel to said edge, means connecting the rack and form as a unit, a member adjacent to said edge for pressing the work against said edge, means for applying pressure to said member, a mounting for said member and means positioned in a substantially fixed proximity to said edge, a gear operatively engaging the rack, a motor driving said gear, a support rotatively mounting the gear and its drive motor, means 35 connecting said mounting and support as a unit, and means on the support for rotating the gear, said units being relatively movable, responsive to rotation of the gear to progressively subject the work to said pressing member, and to thereby 40 progressively conform the work to said form.
16. A bending machine for elongated tubular work having a longitudinal slot comprising a bending form having an edge of the contour to be imparted to the work, a carriage having projections at opposite sides of said edge, a mandrel 45 inserted in the work, a holder for the mandrel mounted on the carriage between its said projections, a driving connection from the holder to the mandrel passing through said slot, means on the carriage for generating pressure, a lever pivotal on the carriage for applying such pressure to the mandrel holder and toward the work, means for guiding the carriage along said edge, and means for driving the carriage along said 50 edge.
17. A bending machine for elongated work comprising a bending form having an edge of the contour to be imparted to the work, a shoulder interrupting said edge and a chamber opening in such shoulder in alignment with a straight 55 portion of said edge for receiving an end portion of the work, and means within the chamber for clamping said end portion against the form during a bending operation.
18. A bending machine for elongated work 5 comprising a bending form having an edge of the contour to be imparted to the work, a shoulder interrupting said edge, and a chamber opening in such shoulder for receiving an end portion of the work, a cam in said chamber for clamping 10 said end portion therein during a bending operation, and means having a fixed operating relation to the cam for rotating the cam.
19. A bending machine comprising a bending form having a work-engaging periphery, a rail spaced from and substantially parallel with said periphery, a carriage movable along said periphery, and mounted jointly on the peripheral portion of the form and on the rail, means on the carriage for applying bending pressure to the 15 work, coacting means on the carriage and the peripheral portion of the form for holding the carriage in a substantially definite proximity to said periphery, and means reacting with the rail to advance the carriage.
20. A bending machine as set forth in claim 19, the last-mentioned means including a motor connected to the carriage and movable therewith along said periphery.
21. A machine for bending a length of longitudinally slotted tubular molding comprising a bending form having a work-engaging periphery, a mandrel slidable in the molding, a mandrel holder, a member adapted to pass through the molding slot and pivoting the mandrel on the 25 holder, whereby the mandrel may angularly conform itself to said periphery, an applicator effective on the holder to press the mandrel against the molding, means for relatively shifting the form and applicator to progressively impose applicator pressure on the molding, and means for maintaining the working relation of the applicator and holder, adjustable to vary such relation.
22. In a machine for bending a length of longitudinally slotted tubular molding, a bending form 30 having a work-engaging periphery a mandrel slidable in the molding, a mandrel holder, an applicator carrying the holder and effective on the holder to press the mandrel against the molding, the applicator having a chamber where- 35 in the holder is fitted, a pressure transmitting connection between the holder and mandrel, said connection being established through the slot of the molding, and means for relatively shifting the form and applicator to progressively impose applicator pressure on the molding.
23. A bending machine comprising a bending form having an edge of the contour to be imparted to the work, mechanical means for wrapping an elongated piece of work around said edge, 40 the form having a chamber in part aligned with a portion of said edge, whereby an end portion of the work may be entered in the chamber preliminary to a bending operation, a clamping element within such chamber effective upon said end portion of the work to hold it fixed, actuating means for the clamping element carried by the form, said means being effective to maintain a clamping pressure throughout an operation of the wrapping means, and a core member carried by the form 45 within said chamber and engageable within tubular work as such work is entered in the chamber and preventing collapse of such work under pressure of the clamping element.
24. Apparatus for bending straight lengths of 50

metallic stock into curvilinear formations, comprising a bending form having two substantially parallel elongated edges, of desired but irregular curvilinear shape, one of such edges facing inwardly and the other outwardly, a traveling bender embracing a portion of the form so as to be movable along said edges, a sprocket chain immovably affixed to and extending along said inwardly facing edge, and conforming to the curvature of such edge, the cross pins of said chain constituting equi-spaced rack teeth adapted to conform themselves to the curvature of the

form without alteration of pitch through all variations of the irregular pitch line required to follow said curvature, a drive sprocket connected to said traveling bender to mesh with said sprocket chain, means to rotate said sprocket, and bending means carried by said traveling bender to oppose and cooperate with said outwardly facing edge of the form, the stock to be worked being disposed between said bending means and said outwardly facing edge. 5 10

GEORGE R. GOIN.
